UNITED STATES PATENT OFFICE

WILLIAM K. SAWYER, OF DETROIT, MICHIGAN, ASSIGNOR TO MORGAN & WRIGHT,
OF DETROIT, MICHIGAN, A CORPORATION OF MICHIGAN

BREAKER FABRIC AND METHOD OF PREPARING THE SAME

Application filed April 6, 1926. Serial No. 100,170.

This invention relates to a new and improved fabric for the manufacture of rubber goods, and more particularly a breaker fabric for incorporation in tires and to the 5 method of making the same.

Incident to the manufacture of tires by what is known as flat building process in which the constituent plies and strata of rubber are assembled on a flat drum and subsequently 10 transformed to approximately tire shape by bulging out the intermediate portion of the "pulley band" carcass, it has been found that the usual breaker fabric of square woven material materially frequently breaks 15 or ruptures and in consequence produces a faulty tire.

The present invention aims to provide a new and improved fabric having a capacity to increase in width or length or both width and 20 length far beyond the elasticity of the constituent yarns or other association of the individual fibres making up the cords of which the fabric is woven. More particularly it aims to provide a breaker fabric which when 25 incorporated in tires will not rupture in the step of inflating or otherwise transforming from flat to tire shape. Other objects and advantages of the invention will be apparent to one skilled in the art.

30 This application is a continuation in part of applicant's previously filed application Serial No. 620,226, filed Feb. 20, 1923.

This invention is illustrated in the accompanying drawings in which:

35 Figure 1 is a plan view of a breaker fabric.

Figure 2 is an elevation of a cord of the same with the central core partially exposed or uncovered, and

40 Figure 3 illustrates a method of wrapping the yarns around the central core.

Referring to the drawings the fabric indicated at 25 is shown composed of the warp threads 26 and filling threads 27. The fabric may be woven in any suitable and convenient manner. The cords shown in Figures 2 and 3 may represent either the warp or the filling thread or both, as the capacity to increase in dimension may be desired either 45 or both lengthwise and crosswise the fabric.

Each cord as shown in Figures 4 and 5 comprises a central core 28 which may be made of a central yarn or a plied yarn about which central core are wrapped spirally one or more 55 yarns 29, preferably a plurality as shown in Figure 5, the pitch of which may be varied to control the capacity thereof to elongate beyond its normal length.

After the fabric is woven or otherwise associated in the form of a strain resisting fabric, it has applied to it vulcanizable rubber composition. The composition may be applied by dipping, calendering, or in any other manner suitable and convenient to the manufacturer of the articles. During the treatment of the fabric it is subjected to stresses which it is the function of this invention to have borne by the central core 28. And this central core 28 may be of any suitable construction sufficient to furnish this requisite 70 strength and preferably of no greater strength than necessary to permit application of the rubber to the fabric.

After the fabric has been rubberized, it may be built into the tire or other article, but 75 preferably in order to get uniform results, the fabric is first subjected to strain in one or both directions, as may be required in order to straighten out the cords of the fabric. For this purpose any suitable and convenient apparatus may be employed.

Having treated the fabric with rubber solution or suspension, and having stretched the fabric after this treatment, and subsequently drying the treated stretched fabric, the latter is then skim-coated with rubber in the usual manner, the rolls of the calender travelling at equal surface speeds in order to prevent distortion of the fabric.

The central core 28 is made strong enough to withstand the stresses incident to stretching the fabric as described and also the strains such as it is subjected to in passing through the calender. This core is not designed to be strong enough to withstand the 80 stresses incident to road use in the tire and as ordinarily made it frequently ruptures 85 when the "pulley-band" is transformed to approximately tire shape by bulging out the intermediate portion of the "pulley-band" car- 100

cass. When the core breaks, instead of having a defective breaker strip as would happen if the breaker strip were constructed as ordinarily made, the applicant's breaker strip is 5 still a continuous woven cloth. The spirally wound yarns merely elongate and there remains an unbroken fabric, the warp and filling thread of which at the parts of the fabric where the core has ruptured consisting of 10 the elongated spirals of yarn.

For some applications, it is preferable to have the central cores, with their spiral wrappings of yarn, forming either the warp or the filling portion of the fabric, depending 15 upon the direction taken by the stresses in the finished article. If the stretch desired is in longitudinal direction, and very little stretch is desired across the fabric, then only the longitudinal cords need contain the central core with the spiral wrappings. The 20 tenter device in this case need exert only a longitudinal pull. Again, if the desired stretch in the final article is to be lateral only, then only the lateral cords need contain the central core and spiral wrappings on the core. Another type of fabric within the scope of the 25 invention, in its broadest sense is woven on the bias. Instead of treating the fabric with a solution of rubber, it may be "frictioned" with rubber on a calendar whose rolls travel 30 at differential surface speeds. In this case, the central cores of the cords must be strong enough to withstand the grinding or wiping caused by the calendar rolls.

35 Having thus described my invention what I claim and desire to protect by Letters Patent is:

1. A fabric for incorporation in rubber articles having each cord consisting of an inelastic easily rupturable central element of 40 sufficient strength only for resisting stresses incident to rubberizing and preparing the article and a covering yarn wound spirally thereabout for holding the fabric together 45 upon rupture of the central element in the finished rubber articles, said fabric being impregnated with rubber.

2. A fabric for incorporation in rubber articles subject to strain the cords of which are 50 composed of an easily rupturable core of relatively weak and inextensible fibrous material surrounded by a stronger and extensible fibrous sheath.

55 3. A fabric for incorporation in rubber articles subject to strain the cords of which are composed of an easily rupturable core of relatively weak and inextensible fibrous material surrounded by a stronger and extensible spirally wound fibrous sheath.

60 4. A fabric for incorporation in rubber articles subject to strain composed of a warp and weft, at least one of which is formed of cords provided with an easily rupturable 65 core of relatively weak and inextensible fi-

brous material surrounded by a stronger and extensible spirally wound fibrous sheath.

5. A rubber article having incorporated therein fabric comprising cords having an easily rupturable central fibrous core and a 70 strong sheath of longitudinally extended spirally wound yarn.

6. A rubber article having incorporated therein breaker fabric composed of a warp and weft, at least one of which is formed of 75 cords provided with an easily rupturable fibrous core surrounded by an extensible sheath of spirally wound yarn.

Signed at Detroit, in the county of Wayne and State of Michigan, this 23rd day of 80 March, 1926.

WILLIAM K. SAWYER.

CERTIFICATE OF CORRECTION.

Patent No. 1,756,069.

Granted April 29, 1930, to

WILLIAM K. SAWYER.

It is hereby certified that error appears in the printed specification of the above numbered patent requiring correction as follows: Page 1, line 14, strike out the word "materially"; same page, line 51, for "Figures 4 and 5" read "Figures 2 and 3"; and that the said Letters Patent should be read with these corrections therein that the same may conform to the record of the case in the Patent Office.

Signed and sealed this 22nd day of July, A. D. 1930.

(Seal)

**Wm. A. Kinnan,
Acting Commissioner of Patents.**
